UNITED STATES PATENT OFFICE.

BENTON J. FIELD, OF LEAKSVILLE, NORTH CAROLINA.

DENTAL IMPRESSION-CUP.

SPECIFICATION forming part of Letters Patent No. 274,299, dated March 20, 1883.

Application filed November 1, 1882. (No model.)

To all whom it may concern:

Be it known that I, B. J. FIELD, of Leaks-
ville, in the county of Rockingham and State
of North Carolina, have invented certain new
and useful Improvements in Dental Impression-
Cups; and I do hereby declare that the follow-
ing is a full, clear, and exact description there-
of, reference being had to the accompanying
drawings, and to the letters of reference marked
thereon, which form part of this specification.

This invention relates to an improved de-
vice to be employed in connection with the
dental impression-cups, which are used to hold
the wax, plaster, or other material when tak-
ing the impression of the upper part of the
mouth for the purpose of forming the dental
plate for artificial teeth; and it has for its ob-
jects to provide certain means whereby the
wax, plaster, or other material may be confined
to the cup and prevented from passing too far
back into the mouth, which causes restlessness
and retching, and renders it difficult to
obtain a perfect impression.

The invention further has for its objects to
provide for forcing the plaster, wax, or other
material into all the irregularities of the mouth
and between the teeth, if there be any, and to
indicate to the dentist the proper length of the
denture by marking the line of juncture of the
hard and soft palate, as more fully hereinafter
specified.

These objects I attain by the means illus-
trated in the accompanying drawings, in
which—

Figure 1 represents a perspective view of a
dental cup, showing my improvement applied
thereto; and Fig. 2 a longitudinal sectional
view of the same.

The letter A indicates a dental cup of the
ordinary or any approved description, which
is provided with the usual handle, D.

The letter E indicates a plate or stop, which
may be constructed of metal or other suitable
material, which is attached to one end of a
spring arm or arms, F, secured in any conven-
ient manner to the handle D. In the present
instance the arms are constructed of steel or
other spring-wire bent and coiled at each side
at the rear, as indicated by the letter G, and
provided with a central bend, H, extending for-

ward, forming a base, which may be secured
to the handle by means of a screw, I, or other
fastening device.

As constructed it will be observed that the
device may be applied to any dental cup. The 55
stop when the device is in place is just at the
rear edge of the plate. When the cup is in-
serted in the mouth, the stop, by reason of the
spring-support, will yield and adapt itself to
the depth of the roof of the mouth, and by 60
pressing upward after passing the line of the
hard palate will indicate to the dentist the line
of juncture of the hard and soft palates, thus
enabling him to construct the palate of proper
length. By confining the wax or other mate- 65
rial the same will be forced into all the cavi-
ties and irregularities in the roof of the mouth,
thus insuring a perfect impression.

In some instances the device may be secured
directly to the cup instead of the handle, if 70
found convenient.

Having thus described my invention, what I
claim, and desire to secure by Letters Patent,
is—

1. An improved device to be employed in 75
connection with a dental impression-cup, the
same consisting of a stop or plate secured to
a spring-arm, which is adapted to be secured
to the said impression-cup, substantially as
specified. 80

2. The combination, with a dental cup, of a
stop or plate extending upward at the rear of
the cup and secured to a spring-arm, which is
secured to the handle of the cup and adapted
to operate substantially as specified. 85

3. The combination, with the stop or plate,
of the spring-arms, constructed of wire, bent
into coils at the rear and formed with a cen-
tral forward bend, by which it may be secured
to the handle of a dental cup by means of a 90
screw or other fastening device, substantially
as specified.

In testimony that I claim the foregoing as
my own I affix my signature in presence of two
witnesses.

BENTON JEREMY FIELD.
